UNITED STATES PATENT OFFICE.

JULIAN PLASZKIEWICZ, OF ALBANY, NEW YORK.

CLOTHES-BOILER.

1,192,452.

Specification of Letters Patent. Patented July 25, 1916.

Application filed February 7, 1916. Serial No. 76,673.

To all whom it may concern:

Be it known that I, JULIAN PLASZKIEWICZ, a subject of the Czar of Russia, residing at Albany, in the county of Albany and State 5 of New York, have invented certain new and useful Improvements in Clothes-Boilers, of which the following is a specification.

This invention relates to certain new and useful improvements in clothes boilers.

10 The primary object of the invention is the provision of a laundry device in the form of a boiler for clothes, the same being adapted for maintaining a continuous circulation of the boiling fluid containing the clothes and 15 the clothes within the boiler being more quickly cleaned thereby.

A further object of the device is to provide a boiler for clothes especially adapted for employment with two separate heating 20 burners and whereby the fluid within the boiler is caused to circulate centrally and upwardly thereof continuously during the clothes boiling and cleaning operation.

With these general objects in view and 25 others that will appear as the nature of the invention is better understood, the same consists in the novel combination and arrangement of parts hereinafter more fully described, illustrated in the accompanying 30 drawings and pointed out in the appended claim.

In the drawings forming a part of this application and in which like-designating characters refer to corresponding parts 35 throughout the several views:—Figure 1 is a longitudinal sectional view of the device taken upon line I—I of Fig. 2. Fig. 2 is a sectional view thereof taken upon line II—II of Fig. 1, and Fig. 3 is a fragmentary transverse sectional view taken upon line III—III of Fig. 2.

It being understood that the present device is in the nature of a boiler for soiled clothes and adapted to receive a cleansing 45 liquid with the clothes merged therein, a boiler 10 having a bottom 11 and a cover 12 of substantially the usual form is herein illustrated provided with the present invention.

50 A false bottom 13 is arranged within the boiler 10 being removably seated upon the bottom 11 by means of an inturned flange 14 carried by an annulus or edge portion 15, it being understood that the flange 14 is 55 parallel with the false bottom 13.

Oppositely positioned tapered casings 16

are carried by the false bottom 13 being secured thereto by rivets 17, the said casings being in axial alinement with the false bottom 13 and when attached to the lower side 60 thereof have bottom members 18 arranged upon the boiler bottom 11, while the opposite outer ends 19 of the said casings are closed, the inner smaller ends 20 of the casings being open.

The false bottom 13 is easily positioned within and removed from the boiler 10 being spaced slightly from the sides thereof when operatively arranged, the said false bottom being provided with a plurality of perforations 21 throughout substantially its entire surface excepting the opposite spaces arranged adjacent the opposite outer portions of the casings 16, it being understood that the said closed portions of the false bottom 13 70 lie adjacent the closed portions of the casings 16, the latter having side perforations 22 only throughout the tapered end portions or halves thereof.

It will be understood from this detailed 80 description of the invention that when the false bottom member 13 is positioned within the boiler 10 and the boiler is partially filled with cleansing liquid and the clothes to be cleaned are arranged within the liquid 85 and the lid 12 is placed in position, the boiler 10 will be arranged over the two spaced burners 23, the latter being illustrated in dotted lines in Fig. 1 of the drawings. The portion of the casings 16 directly above the burners 23 is entirely enclosed with the exception of the inner ends 90 of the casings, so that the heating of the water within the closed portion of the said casing 16 causes such water to flow outwardly through the tapered portions of the said casings and the bottom perforations 21 positioned adjacent thereto and centrally of the boiler 10, the same being effected by reason of the raising of the temperature 100 within the said casings to a higher degree than the temperature of the fluid throughout the boiler 10. The fluid from the casings will then rise substantially centrally of the boiler and this action will continue, 105 thus setting up a continuous circulation of the fluid within the boiler and agitating the clothes contained therein for assisting in cleansing the same.

It will thus be seen that an attachment for 110 a clothes boiler is arranged which may be positioned in the usual form of boiler now

in use and by means of which the circulation of the fluid is effected and the operation of cleaning the clothes is rendered more effective.

5 While the form of the invention herein shown and described is what is believed to be the preferred embodiment thereof, it is nevertheless to be understood that minor changes may be made therein without departing from the spirit and scope of the invention as claimed.

10 What I claim as new is:-

15 As an article of manufacture, a boiler attachment comprising a perforated false bottom, a side edge portion surrounding the said bottom and having an inturned flange parallel with the bottom, oppositely ar-

20 ranged tapered casings carried by the said bottom arranged inwardly of and substantially of the same width as the said edge portion, the said casings being closed at their enlarged outer ends and being provided with closed bottoms in the same plane as the said flange, the said casings being 25 provided with perforations through the opposite sides thereof, adjacent their inner smaller ends, the inner ends of the said casings being open and the portions of the said bottom, lying adjacent the said closed end portions of the said casings and being im- 30 perforate.

25 In testimony whereof I affix my signature.

30 JULIAN PLASZKIEWICZ.

Copies of this patent may be obtained for five cents each, by addressing the "Commissioner of Patents, Washington, D. C."
